DRIFT ELIMINATOR ASSEMBLY FOR COOLING TOWERS

Donald R. Baker, Blue Springs, and Homer E. Fordyce,
Gashland, Mo., assignors to The Marley Company,
Kansas City, Mo., a corporation of Delaware

Application July 16, 1956, Serial No. 598,174

9 Claims. (Cl. 183—26)

This invention relates to improvements in water cooling towers wherein heat is removed from the water by surface evaporation, and particularly to improvements in drift eliminators for towers of such nature, the primary object being to provide effective elimination of water from the outgoing air with minimum pressure loss.

In cooling towers wherein water is cooled as a consequence of the movement of air therethrough, a substantial amount of the water is carried from the tower by the air unless means is provided within the path of travel of the air to eliminate the water and redirect the same downwardly to the intended point of collection within a sump underlying the fill assembly.

Reference may be had to U.S. Letters Patent No. Re. 21,794, issued in the name of Leon T. Mart, on May 6, 1941, for an understanding of the type of water cooling tower to which the instant invention relates and the nature and disposition of conventional drift eliminators commonly employed therein. The same are employed not only in crossflow towers, but in those operating on a counterflow principle as evidenced by U.S. Letters Patent No. 2,672,328, issued March 16, 1954.

While drift eliminators heretofore suggested and/or employed in this field have effectively and efficiently served both functions of guiding or turning the air as it emanates from the fill assembly in the direction of discharge from the tower, as well as remove a substantial amount of the water from the air, it is an important object of the instant invention to provide a drift eliminator that performs both functions still more efficiently, all by virtue of the form and construction of the vanes thereof as well as the supports or spacers utilized to hold the vanes in proper arrangement.

Another important object of the present invention is to provide a drift eliminator that advantageously utilizes the differences in the mass of water and air to cause separation thereof within the eliminator and prior to ultimate discharge of the air from the tower.

A further object of the instant invention is to provide an improved drift eliminator that automatically redirects the water removed from the air into gravitating streams channeled along the supports for the vanes, thereby minimizing the drift from the unit.

A still further object of the present invention is to provide an eliminator that gently turns the air in the direction of flow thereof from the tower as gravity tends to increase the angle of impingement of the water on the vane surfaces, thereby increasing the effectiveness of the vanes as drift eliminators.

In the drawings:

Figure 1 is a side elevational view of a water cooling tower, parts being broken away to show a drift eliminator made pursuant to one form of the instant invention.

Fig. 2 is a cross-sectional view taken on line II—II of Fig. 1.

Fig. 3 is a fragmentary, cross-sectional view of a drift eliminator embodying another form of the instant invention, taken on line III—III of Fig. 4, certain parts

2.

thereof being broken away to reveal details of construction.

Fig. 4 is a fragmentary, cross-sectional view showing the eliminator of Fig. 3 in elevation taken on line IV—IV of Fig. 3, parts being broken away for clearness.

Fig. 5 is an elevational view of another type of water cooling tower, parts being broken away to reveal a drift eliminator made pursuant to another embodiment of the instant invention.

Fig. 6 is an enlarged, fragmentary, vertical, cross-sectional view through a portion of the eliminator shown in Fig. 5; and

Fig. 7 is a fragmentary, cross-sectional view taken on line VII—VII of Fig. 6.

In all essential respects, cooling tower 10 shown in Fig. 1 of the drawings, is the same as that illustrated in the aforementioned Patent No. Re. 21,794, in that water is cooled through use of fill assemblies broadly designated by the numeral 12 and through which air is forced by use of a fan unit 14. Hot water is collected in an open top basin 16 for distributing the same to the assemblies 12 therebelow. Intermediate basins 18 between the assemblies 12, collect the cooled water and transfer the same laterally whereby to redistribute the same to the assembly therebelow. The cooled water is collected in a sump for passage to a point of use in the same manner as shown and described in the last mentioned patent.

It is seen that the air flows horizontally through the assemblies 12 in crossflow relationship to the gravitating water, and the hot air is ultimately discharged vertically from the tower 10 through outlet 20 within which the fan assembly 14 is disposed. The force of air causes the gravitating water to drift laterally at an angle to the vertical substantially as the assemblies 12 are inclined in Fig. 1, and therefore, it becomes necessary to provide drift eliminator broadly designated by the numeral 22 within the tower 10 at the outlet ends of the assemblies 12 to remove the water entrained in the air and redirect the same downwardly to the underlying sump.

Eliminator 22 shown in Figs. 1 and 2, is of special construction differing substantially from those heretofore employed in this field for the purpose of more effectively removing the water and controlling the direction of air flow so as to minimize pressure loss. To accomplish these results the eliminator 22 consists of a plurality of horizontally aligned supports 24 that are preferably rectangular and disposed with their longitudinal axes inclined downwardly and inwardly toward the underlying sump and such inclination also disposes the transverse axes of the supports 24 on an incline opposite to the direction of inclination of the longitudinal axes of supports 24. It is thus seen that both longitudinal edges of the supports 24 are inclined, but, as seen in Fig. 2, it is to be preferred that the opposite faces of the supports 24 be vertical.

As will hereinafter appear, the horizontal spaced supports 24 serve a dual function, namely, that of supporting elongated vanes or slats 26, as well as channel the removed water downwardly in streams toward the underlying cold water collecting sump. Vanes 26 have opposed flat faces and are arranged in a plurality of end-to-end sections 28, 30 and 32, the number of such sections varying however, in accordance with the size of the tower 10 with which the eliminator 22 is to be used.

Vaness 26 are carried by the supports 24 through any suitable means of attachment thereto, as for example, the interlock arrangement employed in the splash deck assemblies of Patents 2,330,901 and 2,342,952. In any event, both the longitudinal and transverse axes of all of the vanes 26 are inclined. The longitudinal inclina-

tion of the vanes 26 is seen in Fig. 2 of the drawings and it is to be noted that the direction of inclination of the vanes 26 of section 28 is opposite to the direction of inclination of the vanes 26 of section 30.

Where possible, it is to be desired that the vanes all incline downwardly and inwardly toward a center line with respect to the vertical axis of rotation of fan 14. In other words, if, for example, a drift eliminator is provided with four end-to-end sections, the fourth section disposed to the left of section 28, would have its vanes incline in the same direction as the vanes 26 of section 28 and, therefore, oppositely to the direction of inclination of vanes 26 of the two sections 30 and 32.

The inclination of the vanes 26 transversely thereof is seen in Fig. 1 of the drawings and it is apparent that desirably such angle of inclination be approximately 45 degrees, thereby bisecting the angle between the horizontal path of travel of the air as it emanates from the assemblies 12, and the vertical path of travel thereof as the air moves upwardly through the outlet 20. Consequently, all of the air and water entrained therein, strikes the innermost inclined faces of the vanes 26 and is gently turned or redirected upwardly toward the outlet 20. While the air and water move at substantially the same velocities, the air tends to move upwardly and thereby separate from the water as the latter, being substantially heavier, tends to continue moving horizontally against the vanes 26.

While much of the water thus removed gravitates forthwith from the eliminator 22 to the collecting sump therebelow, a substantial amount of the removed water flows longitudinally of the vanes 26 and water that does not drop from the lowermost edges of the vanes 26 by virtue of the transverse angularity of the latter, moves against the inclined supports 24 by virtue of the intersecting relationship of the vanes 26 and the supports 24.

When the water channeling along the vanes 26 longitudinally thereof strike the upright supports 24, its direction is changed and such water thereupon either gravitates from the vanes 26 adjacent the supports 24, or channels downwardly along the latter in a plurality of streams to the water collection basin.

It is to be noted further that the vertically spaced vanes 26 are relatively overlapped so that at no point throughout the entire area of the eliminator 22, is it possible for any air and water to flow therethrough without being subjected to the removal action just above described.

Still another advantage of longitudinal inclination of the vanes 26 lies in the fact that the removed water is caused to flow in one direction and thereby separate from the air as the action of fan 14 continues to move the latter and prevents such air from flowing with the water toward the lowermost ends of the vanes 26. Thus the stop is knocked out of the droplets of water which are separated from the air. In other words the tendency of the droplets to stop and remain on the slats 26 is eliminated since due to the double inclination of the upper surfaces of slats 26 the droplets are deflected downwardly in two directions to facilitate gravitation of the same along the slats.

In Figs. 3 and 4 of the drawings there is provided a drift eliminator 34 composed of a pair of banks 36 and 38, the bank 36 being proximal to the fill assembly of the cooling tower (not shown in Figs. 3 and 4), and the bank 38 being proximal to the air outlet of the tower. In all respects the bank 38 is identical with the drift eliminator 22 and need not be further described. The bank 36 however, differs in that the transverse angle of inclination of its vanes 40 is less than the angle of transverse inclination of vanes 42 of the bank 38. Furthermore, as seen in Fig. 4, the vanes 40 incline longitudinally thereof in a direction opposite to the direction of inclination of the longitudinal axes of the vanes 42. In other words, the bank 38 is subdivided into a plurality of end-to-end sections 44 and 46 as in the case of the

eliminator 22, and the bank 36 is likewise subdivided into a plurality of corresponding sections 48 and 50 respectively.

Fig. 4 of the drawings illustrates clearly the way in which the longitudinal axes of the vanes 40 of section 48 incline oppositely to the longitudinal axes of the vanes 42 of section 44. The same arrangement is provided between the vanes 40 and 42 of sections 50 and 46 respectively.

At least two additional advantageous results are made possible through use of eliminator 34 not included in the principles of the eliminator 22. First, as the water entrained air impinges upon the uppermost and innermost faces of the vanes 40 the direction of travel thereof is changed slightly, but the turning action is increased more sharply as the same impinges upon the uppermost and innermost faces of the vanes 42. In this respect therefore, the water and air tend to separate within the bank 36 of the eliminator 34 and more complete separation takes place as the direction of travel of the air more closely approaches the vertical within the bank 38 and as the water is deflected from the upper surfaces of the vanes 40 to the upper surfaces of the vanes 42.

Still further, it can be seen by comparing Figs. 3 and 4, that the air and water are forced through a tortuous path of travel within eliminator 34 since the vanes 40 tend to cause movement upwardly in one direction longitudinally thereof and as soon as the air and water reaches the bank 38, its course is changed and the same tends to move upwardly at an angle in the opposite direction along the longitudinal axes of the vanes 42.

In any event however, removed water channeling along the vanes 40 comes into contact with inclined spacers or supports 52 that intersect the vanes 40 and water channeling in the opposite direction longitudinally of the vanes 42, comes into contact with inclined supports 54 for the vanes 42. Such channeling induces gravitational flow of the removed water in streams following the longitudinal axes of the supports 52 and 54, thereby more effectively eliminating the water from the outwardly moving hot air, all without appreciable pressure loss.

The cooling tower illustrated in Fig. 5 of the drawings is much in the nature of one of the forms disclosed in Patent No. 2,672,328 and illustrates the manner of carrying the principles of the instant invention through use of a generally horizontal drift eliminator 56 in a counterflow type of arrangement. In this respect, fan 58 directs the air vertically through the fill assembly (not shown) in a direction opposite to the flow of water emanating from nozzles 60 of manifold 62, the cool air entering below the fill through inlets 64.

Eliminator 56 includes a plurality of sections 66 having adjacent sections inclined oppositely as seen in Fig. 5. Each section includes a plurality of horizontally spaced, longitudinally horizontal and transversely inclined supports or spacers 68. Each section 66 is also provided with two banks 70 and 72 of eliminator vanes 74. All of the vanes 74 are longitudinally inclined as seen in Figs. 5 and 6 and transversely inclined as seen in Fig. 7. Furthermore, the vanes 74 are all in intersecting relationship to the supports 68 and preferably pass loosely therethrough. While all of the vanes 74 of any given section 66 are inclined longitudinally in the same direction, the vanes 74 of the lower bank 70 of each section are inclined transversely in a direction opposite to vanes 74 of the upper bank 72.

Furthermore, it is seen that all of the vanes on one side of a central vertical plane through the tower, extending longitudinally of the vanes and passing through the vertical axis of rotation of fan 58, are inclined transversely in one direction and the remaining vanes 74 are inclined in the opposite direction. In other words, in the upper bank 72, vanes 74a are inclined oppositely to vanes 74b of bank 72. Likewise, in the lower bank 70, vanes 74c are inclined transversely in a direction oppo-

site to the direction of transverse inclination of the vanes 74d of lower bank 70.

Here again, the air and water are caused to traverse a tortuous path through the eliminator 56, but in a manner differing from the way in which the tortuous travel is accomplished in eliminator 34. The vertically moving water entrained air striking the lowermost inclined faces of the vanes of bank 70 is deflected laterally from the vertical in one direction toward the lowermost faces of the vanes of the bank 72. When the same impinges upon the lower faces of the vanes of bank 72, the direction of travel is again deflected in the opposite direction toward the fan 58. Each time that the direction of travel of the water entrained air is changed, the differences in weights between the water globules and the air particles causes the water to separate from the air. In other words, as the air impinges upon the vanes, its course of travel is rather easily changed, whereas the water being heavier tends to continue its normal course and be deflected at a different angle from the angle of deflection of the air.

In virtually all other respects, the eliminator 56 operates the same as the eliminator 34 and for that matter, the eliminator 22, since the removed water channeling downwardly at an angle longitudinally of the vanes 74 either gravitates from the lowermost edges of the vanes 74 or moves to a point where its downwardly inclined travel is intercepted by the spacers 68.

It is now apparent that in all three forms of the invention there has been presented a drift eliminator capable of maximum removal of water from the hot air that tends to drift therewith from the fill assembly to the hot air outlet of the tower. At the same time, each of the eliminators is so constructed as to gradually, progressively and gently change the course of travel of the air, thereby increasing the separating action of the water therefrom and doing so without pressure loss.

It is recognized that any obstacle to the flow of air tends to produce a drop in pressure, but it has been found that through use of the eliminators of the kind above described, such pressure loss is of virtually no consequence and, therefore, a minimum amount of water is carried from the tower by the hot air, all without any deleterious effects whatsoever upon the overall efficiency of the system.

Having thus described the invention what is claimed as new and desired to be secured by Letters Patent is:

1. In combination with a water cooling tower having an air inlet, an air outlet and means for directing currents of air along a path of travel from the inlet to said outlet in substantially horizontal, intersecting relationship to water gravitating within the tower, a drift eliminator within the tower, disposed to remove droplets of water from the air immediately prior to discharge of the air through said outlet, said drift eliminator comprising a plurality of elongated slats, each having a pair of opposed flat faces, and structure supporting the slats in an inclined stack intersecting said currents of air with the upper slats of said stack disposed in closer proximity to said inlet of the tower than the lower slats of the stack, said slats being parallel, disposed in vertically spaced

relationship with the longitudinal axes thereof inclined transversely of said path of travel of the air and the transverse axes of the upper faces thereof transversely inclined whereby to present a double slanted uppermost face on each slat respectively, said double slanted faces being disposed for direct impingement of the moisture laden air thereagainst to deflect the latter upwardly and outwardly toward said air outlet while the droplets of water in said moisture laden air are deflected downwardly with the stop being knocked out of the same and causing the water to gravitate rapidly down respective slats out of the high velocity air currents.

2. The combination as set forth in claim 1 wherein said supports include a number of horizontally spaced, upright, parallel, elongated, longitudinally and transversely inclined members.

3. The combination as set forth in claim 1 wherein is included a pair of said stacks disposed in parallel, horizontally spaced relationship, the longitudinal axes of the slats of one stack being inclined in one direction and the longitudinal axes of the slats of the other stack being inclined in the opposite direction.

4. The combination as set forth in claim 3 wherein said stacks lie in planes intersecting the path of travel of said currents of air.

5. The combination as set forth in claim 4 wherein said stacks are aligned and disposed in horizontally spaced planes whereby the slats of one stack are in crossed relationship to the slats of the other stack.

6. The combination as set forth in claim 5 wherein the pair of stacks are disposed in sufficient proximity that one of the stacks is in overlying, superimposed relationship to the other stack.

7. The combination as set forth in claim 1 wherein said stacks are subdivided into a plurality of end-to-end sections, the direction of longitudinal inclination of the slats of certain sections differing from the direction of longitudinal inclination of the slats of other of the sections.

8. The combination as set forth in claim 3 wherein the angle of transverse inclination of the transverse axis of the slats of one of the stacks is greater than the angle of transverse inclination of the transverse axis of the slats of the other stack.

9. The combination as set forth in claim 8 wherein the stack having slats disposed in greatest transverse angular inclination is located in closest proximity to the air outlet of the tower.
